DOOR LATCH

Fred C. Schoch, Oak Park, Ill.

Application October 3, 1934, Serial No. 746,666

4 Claims. (Cl. 292—1)

This application is a continuation in part of my previously filed application, Serial No. 718,712, filed April 2, 1934.

This invention relates to improvements in door fastening means, and refers specifically to the provision of a door fastening device, particularly adapted for automobile doors and the like, where-in the handle or knob which actuates the fastening mechanism is rendered inaccessible when the device is in locked position. One of the important objects of my invention is the provision of simple means by which the handle of a door, such for example as an automobile door, may be protected against damage either by being struck by some other object or twisted intentionally in an effort to open the door.

Also, another feature of the invention is to provide a door fastening means which may be incorporated in a door of conventional construction and adapted to the existing lock without material change in these parts, or departure from established practice.

Another object of the invention is to provide a structure of the class described which is of highly simplified construction, durable in use and comparatively economical to manufacture.

Other objects and advantages of my invention will be apparent from the accompanying drawings and following detail description.

30 In the drawings, Fig. 1 is a fragmentary, elevational view illustrating the application of my improved door fastening means.

Fig. 2 is a horizontal, sectional view taken on line 2—2 of Fig. 1 with the handle of the door fastening means disposed in the associated recess so that the handle is protected against being turned or knocked off.

Fig. 3 is a fragmentary, horizontal, sectional view illustrating the handle in locked and unlocked position.

Fig. 4 is a sectional view taken on line 4—4 of Fig. 2.

Fig. 5 is a sectional view taken on line 5—5 of Fig. 4.

45 Fig. 6 is a transverse sectional view taken on line 6—6 of Fig. 3.

Fig. 7 is a similar view illustrating the handle in extended position.

Fig. 8 is a view similar to Fig. 4 illustrating the latch in retracted position.

Fig. 9 is an elevational view obtained by looking in the direction of the arrows 9 shown in Fig. 6.

Referring in detail to the drawings, 1 indicates 55 a portion of an automobile body, a door 2 being

particularly illustrated, said door being mounted upon hinges 3. The door may be provided with lock 4 and handle 5. Although my invention is described in conjunction with an automobile door and is particularly adaptable for such use, it is to be understood that the same may be utilized with other types of doors.

The locking mechanism comprising my invention may be carried in substantially its entirety upon plate 6 which may have a portion 7 bent 10 at an angle to the main part of the plate. An aperture 8 may be provided in plate 6 and a collar 9 may be loosely positioned in said aperture. A retaining strip 10 may be secured to plate 6 and the bent extension thereof 7 as shown respectively 15 at 11 and 12 in Fig. 3, said strip being adapted to prevent the accidental displacement of collar 9 from aperture 8.

A pin 13 having a square or other polygonal cross section may be positioned in an opening 20 provided in collar 9, said opening being of similar cross section to that of the pin. A portion of pin 13 may extend beyond the end of collar 9 and may project outwardly from plate 6, said portion being undercut or provided with an annular recess 14. A lug 15, Fig. 9, having bifurcated arms 16 may be adapted to secure pin 13 in desired position, said arms preventing longitudinal motion of pin 13. Lug 15 may be secured to the face of plate 6 by means of screw 17 or the like. 30

Handle 5 may be integrally attached to spindle 18, which may be provided with a longitudinal bore 19 of similar cross section to that of pin 13. As will be hereinafter more fully described, spindle 18 is slidably movable upon pin 13 whereby 35 handle 5 may be positioned either in its advance position, as shown in dotted lines in Fig. 3, or in its locked position, wherein the entire handle may be disposed in recess 20 provided in the outer panel 21 of door 2.

40 A lug 22 may be mounted upon the bent plate 7 and may carry an outwardly projecting portion 24. A cylindrical collar 25 having an end of reduced diameter 26 may be positioned within an aperture provided in the extension 24. When 45 the reduced portion 26 of collar 25 is positioned within said aperture, the end thereof may be flared outwardly so as to rigidly secure collar 25 and the extension 24. Collar 25 may function as a support or guide for spindle 18 in its movements hereinbefore described.

An arm 27 may form an integral portion of collar 9 and as can readily be seen, when handle 5 is rotated thereby rotating pin 13, collar 9 will also be rotated and arm 27 will be rocked. A 55

member 28 may be slidably mounted upon plate 6, said plate being provided with slot 29 in which rivet 30 may be disposed, said rivet being rigidly secured to the member 28 whereby slidable movement of said member may take place in a direction parallel to the length of slot 29. One end of member 28 may comprise latch 31 which is adapted to register with keeper 32, formed in the face plate 33 of the door frame 34. A juxtaposed portion of member 28 may be positioned adjacent the end of arm 27, the relation being such that when arm 27 is rocked, as hereinbefore described, member 28 will be slidably moved, whereby latch 31 may be retracted from keeper 32. A coil spring 35 or other resilient member may operatively secure member 28 and plate 6 whereby latch 31 will be resiliently impelled into registration with keeper 32. When arm 27 moves member 28 so as to retract latch 31, member 28 will be moved 20 against the tension of spring 35.

The inner end of spindle 18 may be provided with an annular groove 36, a notch 37 may connect said groove to the end of said spindle. On the side of the spindle diametrically opposite notch 37, said spindle may be provided with a longitudinal groove 38. A pin 39 may be mounted upon collar 25 and may project inwardly into groove 38.

To assemble the parts hereinbefore described, 30 pin 13 may first be positioned within recess 19 in spindle 18. The spindle and the pin may then be inserted into collar 25, the position of handle 5 being such that slot 37 registers with pin 39. In this manner pin 39 may be brought into the annular groove 36 and handle 5 may be rotated 35 through an angle of 180° until pin 39 lies at the end of the longitudinal groove 38. Spindle 18 may then be moved inwardly through collar 25, pin 39 being positioned in groove 38. When 40 spindle 18 has been pushed inwardly until handle 5 abuts the base of recess 20, the end of pin 13 will project beyond plate 6 and lug 15 may be utilized to anchor the pin in the position shown in Fig. 3. Prior, however, to inserting spindle 18 45 and pin 13 into collar 25, a coil spring 40 may be positioned upon pin 13, said spring being so constructed as to be under compression when spindle 18 is in locked position and, consequently, said spring tends to impel handle 5 out of the recess 50 20 when the device is unlocked, as will be herein-after described.

The strip 11 for retaining collar 9 in position may be provided at its end with an upwardly extending integral flange 41. A lug 42 may be secured to the face of plate 6 as by screws 43 or the like and may also be provided with an upwardly extending flange 44 in a plane parallel to flange 41. Both flanges 41 and 44 may be provided with apertures through which bar 45 may 60 extend. An end 46 of bar 45 may have an arcuate-shaped edge and may comprise a detent which is engageable with spindle 18, the edge of said detent being registerable with the annular groove 36 when the device is in locked position. A spring 65 47 may be positioned between detent 46 and flange 41 and may normally impel said detent toward spindle 18.

Lock 4 may comprise a barrel 48 which may be positioned in an aperture provided in lug 49, 70 which latter is secured to the bent plate 7 by means of screw 50 or the like. Pin 51 may project from the end of barrel 48 and may carry at its end arm 52. A pin 53 may be secured to bar 45 adjacent arm 52.

In operation, the device may be placed into

locked position by pushing handle 5 inwardly toward recess 20. In this position spring 40 is compressed as shown best in Fig. 6 and detent 46 impelled by spring 47 engages with the end of spindle 18. In this manner, spindle 18 will be retained in its innermost position by means of bar 45. As can readily be seen, latch 31, in this position, will be in engagement with keeper 32 and the door cannot be opened.

When it is desired to open door 2 the key may 10 be inserted in lock 4 and barrel 48 may rotate thereby rocking arm 52. Said arm when rocked contacts pin 53 and moves bar 45 in the direction indicated by the arrow in Fig. 7. When the bar is so moved, detent 46 is removed from engagement in groove 36 and, consequently, spindle 18 is urged to its advanced position by means of spring 40 as shown best in Fig. 7. In this position pin 39 registers with the annular groove 36 and handle 5 may be turned thereby rocking arm 20 27 mounted upon collar 9 and retracting latch 31.

It is to be understood that the mechanism comprising lock 4 may be of conventional construction and, consequently, said mechanism is not shown in detail. Said mechanism may be such 25 that arm 52 can be manually rocked in either direction in which case it would be necessary to turn the key in the lock either to lock the door or unlock it. If desired, however, the mechanism of lock 4 may be such that arm 52 will spring 30 back to its original position when the force applied to the key is removed, permitting bar 45 to be moved to its original position after it has been shifted to remove the detent 46 from groove 36. In this case when lock 4 is actuated to shift the 35 detent in the direction as shown by the arrow in Fig. 7, and the force applied to said key is removed, the detent will return to its original position. In either case, after bar 45 has been moved to its original position either by spring 40 pressure or manually, the latch may be locked merely by pushing handle 5 inwardly into recess 20, which action results in the engagement of detent 46 in groove 36.

It can readily be seen that, when spindle 18 45 reaches its outermost position, pin 39 engages with the outer defining edge of groove 36 thereby preventing further outward motion of the spindle 18 and handle 5.

A plate 54 may be positioned adjacent the inner panel of door 2 and may carry spindle 55 upon which handle 56 may be mounted. Spindle 55 may be journaled in plate 54 and also in the spaced plate 57 which may be mounted upon the inner face of plate 54. A collar 58 may be rigidly positioned upon spindle 55 and may carry an integrally attached arm 59, said collar being positioned upon shaft 55 between plates 54 and 57. A notch 60 may be provided in the edge of collar 58 and a leaf spring 61 may bear against the surface of said collar, whereby when handle 56 is rocked, to disengage latch 31 from keeper 32, as will be hereinafter more fully described, spring 61 will return the handle 56 to its original position after the rotating force has been relieved. 65 A link 62 may be pivotally connected at one end to the end of arm 59, said link being provided with an elongated slot 63 at its opposite end. A pin 64 may be mounted upon extension 65 of member 28, said pin being positioned in slot 63. 70

The arrangement is such that regardless of the operative relationship of the key operated mechanism comprising lock 4, bar 45, spindle 18, etc., latch 31 may be disengaged from keeper 32 by rocking handle 56. Moreover, by the provision 75

of the lost motion connection comprising slot 63 and pin 64, member 28 may be moved to the position shown in dotted lines in Fig. 4 without in any way disturbing the position of handle 56.

5 A lug 66 may be mounted upon plate 6 by means of screw 67 or the like, said lug having an outwardly extending flange 68. Flange 68 may be provided with an aperture through which bar 69 may pass. One end of bar 69 may be bent as shown best at 70 in Fig. 4, the bent end being positioned adjacent link 62 between spaced pins 71 and 72 mounted upon said link. The opposite end of bar 69 may be provided with a recess 73 through which bar 45 may be positioned. A pin 10 74 may be positioned upon bar 45 adjacent bar 69, bar 69 being disposed between pin 14 and the outer face of flange 41. The end of bar 69 may be tapered so as to form a cam surface 75.

15 In operation when handle 56 is rocked to move latch 31 outwardly from keeper 32, pin 71 carried by link 62 contacts the bent end 70 of bar 69 and moves said bar in the direction indicated by the arrow in Fig. 4. Upon this movement taking place the inclined cam surface 75 contacts pin 20 14 and moves bar 45 against the compressive force of spring 47 thereby disengaging detent 46 from groove 36 and releasing spindle 18 permitting outward movement thereof.

25 By this construction door 2 may be securely locked as approached from the outside of the automobile, that is, handle 5 may be positioned within recess 20, but movement of the inside handle 56 will release handle 5 and permit it to spring to its outermost position. However, as soon as the force rocking handle 56 has been removed, spring 61 returns handle 56 to its original position and, consequently, pin 72 contacts the bent end 70 of bar 69 thereby permitting detent 46 to be positioned in its normal locking 30 40 position. However, at this phase of the operation spindle 18 is in its outermost position. Hence, when the passenger or driver steps from the car and closes door 2, the detent 46 is in position to receive groove 36 merely by the action of pushing handle 5 into recess 20.

45 As pointed out hereinbefore my invention is particularly adaptable for automobile doors but broadly its use is contemplated wherever the features thereof would be desirable in latching 50 constructions.

I claim as my invention:

1. A door lock having a latch bolt, an outer and an inner handle, said outer handle having a rotatable spindle and a tubular stem contractible lengthwise of the spindle, a trigger latch for holding the tubular stem in contracted position, a slide bar connecting the latch bolt and the inner handle, and means contacting said slide bar as the inner handle is turned in one direction for releasing the trigger latch and for permitting the 10 return of the tubular stem to dispose the outer handle in operative position.

5 2. A door lock having a latch bolt, an outer and an inner handle, said outer handle having associated therewith a rotatable solid spindle and a tubular stem contractible lengthwise of the spindle, a trigger latch for engaging the tubular stem and holding the same in contracted position, a slide bar connecting the latch bolt and the inner handle, and means contacting said slide bar 15 20 as the inner handle is turned in one direction for releasing the trigger latch and for permitting the return of the tubular stem to dispose the outer handle in operative position.

25 3. A door lock having a latch bolt, an outer and an inner handle, said outer handle having a rotatable spindle and a tubular stem contractible lengthwise of the spindle, a trigger latch for holding the tubular stem in contracted position, means operatively connecting the latch bolt and 30 the inner handle to retract the latch bolt when the inner handle is turned in one direction, and means actuated by said turning movement of the inner handle for releasing the trigger latch and for permitting the return of the tubular stem to 35 dispose the outer handle in operative position.

4. A door lock comprising a frame, a latch bolt slidably positioned in said frame, an outer handle for the door journaled in said frame, said outer handle having a rotatable spindle and a 40 tubular stem contractible lengthwise of the spindle, a trigger latch for holding the tubular stem in contracted position, an inner handle for the door, and means operatively connecting said inner handle and said trigger latch to release the 45 trigger latch when the inner handle is turned for permitting the return of the tubular stem to dispose the outer handle in operative position.

FRED C. SCHOCH. 50
